UNITED STATES PATENT OFFICE.

WILLIAM HUBBARD, OF ODON, INDIANA.

CHIMNEY-PROTECTOR.

SPECIFICATION forming part of Letters Patent No. 331,710, dated December 1, 1885.

Application filed July 23, 1885. Serial No. 172,469. (No model.)

To all whom it may concern:

Be it known that I, WILLIAM HUBBARD, a citizen of the United States of America, residing at Odon, in the county of Daviess and State 5 of Indiana, have invented certain new and useful Improvements in Flue-Protectors; and I do hereby declare the following to be a full, clear, and exact description of the invention, such as will enable others skilled in the art to which it 10 appertains to make and use the same, reference being had to the accompanying drawings, and to letters or figures of reference marked thereon, which form a part of this specification.

15 My invention relates to certain new and useful improvements in the construction of chimneys, the object of the same being to provide a device which will prevent the roof leaking around the chimney, and also to provide a means whereby the upward draft will be accelerated, the wind prevented from blowing down the chimney, and the upper portion of the same protected from the weather; and to this end my invention consists in the construction and the combination of the parts, as 20 will be hereinafter fully set forth, and specifically pointed out in the claims.

In the accompanying drawings, which illustrate my invention, Figure 1 is a perspective view of my improvement, and Fig. 2 is a vertical sectional view.

25 A represents the upper portion of the chimney, which may be constructed of brick-work or any other suitable material. Sheet-metal plates *a b* are attached to the metallic casting *A'*, which encircles the chimney above and adjacent to the roof, through which said chimney passes. The lower plate, *b*, lies immediately above the lathing or roofing-boards, 30 while the upper plate, *a*, is located immediately above the shingles. By this construction the roof surrounding the chimney is made perfectly water-tight and the masonry protected from the weather.

45 Adjacent to the upper portion of the chimney-easing *A'* are attached metallic bars or rods *B*, the lower ends of which are bent inwardly and secured beneath the rim or coping of the chimney proper. These rods are secured at their lower ends to the upper part 50 of the easing *A'*, as shown in Fig. 2, and, after

extending a slight distance upwardly, are bent inwardly, the upper tier of bricks of the coping being recessed for this purpose, and to the under side is secured a plate, *C*, the sides of 55 which are bent downwardly, so as to be parallel with the upper horizontal portion of the rods *B*, and one laps the masonry, as shown. Immediately above the horizontal portion of the rods *B* is placed a tier or row of bricks, 60 *D*, which are provided with vertical perforations *e*, through which the vertical portions *f* of the rods *B* pass. Above the bricks *D* is secured a metallic plate, *g*, and above said metallic plate is laid another row of bricks, 65 *D'*. Above the upper tier of bricks, *D'*, is attached a metallic covering-plate, *E*, which is of a sufficient length to overlap the ends of the top *D'*, and the same is bent upwardly at its central portion, as shown. The rods *B* 70 pass through this upper cover, *E*, and are secured thereto by means of nuts *i*, which nuts hold the parts firmly in position.

By means of the device hereinbefore described rain is prevented from beating into the 75 chimney, as well as downward drafts, and the upward draft is accelerated or increased, and thus the draft in the chimney will be increased, so as to prevent the same from smoking. It will also be noticed that as the chimney is increased the masonry-work thereof will be protected from the weather and the separation of the bricks prevented, thus obviating any danger from fire being communicated to the roof at the junction of the same with the chimney. The upper portion of the chimney is 80 also held in place and protected by the rods and plates, as set forth.

I claim—

1. In a device for protecting chimneys, a 90 superstructure composed of alternating layers of brick and metal plates, bent metal bars extending through central openings in said superstructure, and a covering-plate, *E*, with open ends, secured by said bars, substantially 95 as and for the purpose set forth.

2. In combination with a chimney, the rod *B*, having inwardly and upwardly bent portions, as shown, said rod having secured thereto, under the horizontally-bent portion of a 100 plate, *C*, with downwardly-turned sides, one or more plates with central openings and ver-

tical perforations, through which the vertical portions of the rod B pass, and a covering-plate with a central arched portion secured above the frame, the parts being organized 5 substantially as shown, and for the purpose set forth.

3. In combination with a chimney, a casing, A', which extends above and below the roof, the plates *a b*, attached thereto, and the rods B, 10 secured to the upper portion of the casing and

extending through the plates C g E, which are separated from each other by the rows of bricks D D', substantially as shown.

In testimony whereof I affix my signature in presence of two witnesses.

WILLIAM HUBBARD.
